UNITED STATES PATENT OFFICE.

JACOB J. WALTHER, OF DAYTON, OHIO.

GRINDING APPARATUS.

1,412,985.

Specification of Letters Patent. Patented Apr. 18, 1922.

Application filed October 4, 1920. Serial No. 414,583.

To all whom it may concern:

Be it known that I, JACOB J. WALTHER, a citizen of the United States, residing in Dayton, in the county of Montgomery and State 5 of Ohio, have invented certain new and useful Improvements in Grinding Apparatus, of which the following is a specification, reference being had therein to the accompanying drawing.

10 This invention relates to grinding apparatus, having particular reference to grinding machines of an improved type for rough grinding of steel wheel castings to prepare the same for machining operations.

15 As is well known in this art, wheel castings of this character are rough as they come from the mold, portions of the wheel, such as the rim and hub, which require machining operations, having usually more or less scale 20 sand pits and projections of metal which can best be reduced by a grinding operation before the wheel is machined to size.

25 Grinding of steel wheels is more or less dangerous because of the size and weight 25 of the grinding wheels used in the operation and the speed and pressure under which the grinding is done,—the danger arising from the tendency of the grinding wheels to burst. Also the manual labor required in wheel 30 grinding under the common practice is unusually heavy and is objectionable to workmen, especially because of the danger which is ever present. The present invention overcomes these difficulties in most part, as it 35 provides a grinding apparatus which is safe to operate and in which the manual labor required for operating is minimized.

In the accompanying drawings, I have 40 illustrated my invention in a preferred form, but, the essential features and underlying principle of the invention being broadly new, in this art, as far as I am aware, it will be understood that various modifications 45 may be made relative to the details of construction and arrangement here illustrated without departing from the spirit and scope of the invention as defined and contemplated in the appended claims.

Referring to the drawings:

50 Fig. 1 is an elevation of my improved grinding apparatus comprising two grinding units;

55 Figs. 2 and 3 are end elevations respectively of the two grinding units illustrated in Fig. 1; and

Fig. 4 is a plan view of the wheel supporting mechanism.

While my improved apparatus is here shown as comprising two grinding units,—one for grinding the face and the other the 60 edges and hubs of the rims of wheel castings, it will be understood that the apparatus may consist of a single unit or any number of 65 grinding units for performing these operations, the present showing being for the purpose of illustrating the invention only without reference to the specific details of the arrangement.

As here shown, a pit C is provided below the floor line upon which the work is done. 70 Arranged relative to the pit is a frame structure comprising upright supporting beams 1 and an overhead structure 2 which supports an upper drive shaft 3 suspended in hangers 4 and having a belt pulley 5. Power 75 is transmitted to the shaft 3 from a lower drive shaft 6 by means of a pulley 7 and belt 8,—shaft 6 being driven as here shown by means of a pulley 9 and belt 10 whereby the apparatus may be connected to any suitable 80 source, as a motor (not shown), of operating power.

Arranged parallel one with the other on opposite sides and preferably, as here shown, somewhat below the upper edge of the pit 85 are work supporting and operating shafts 11—12,—shaft 11 being connected to lower drive shaft 6 by means of a belt 13 operable over pulleys 14, 15, a counter shaft 16 and reduction gearing 17 whereby the speed of 90 the shaft is stepped down from the speed of the drive shaft. While the driving connections here shown provide for effective operation of the apparatus, it will be understood that no broad novelty is claimed as to 95 these detail arrangements and that any suitable means may be employed for driving and regulating the speed of the same.

Shaft 12 is connected to shaft 11 by means of a chain 18 and sprockets 19,—the sprockets being equal, the shafts are therefore operated at equal speeds and, as shown, in the same direction. Secured to shafts 11—12 are oppositely disposed sets of flanged rollers 20 which are adapted to 100 support and rotate the work to be ground,—the work in the present application of the invention consisting, as stated, of steel cast wheels 21 which set free upon the rollers 20 and are rotated in the direction opposite 105 110

to the rotation of shafts 11-12, the flanges 22 of the rollers serving to prevent lateral displacement of the wheels while the same are being ground.

5 Suspended from overhead drive shaft 3 by means a carrier 23 and beam 24 is the grinder which may be of any suitable construction, consisting as here shown, of a grinding wheel or disc 26, guard 27, cross-head 28, shaft 29, tight and loose pulleys 30-31, belt shifter 32, and controlling handle 33,—the grinder being connected to overhead drive shaft 3 by means of the pulleys 30-31, a pulley 34 and belt 35.

15 The grinder is supported on shaft 3 in a manner to permit of a free swinging movement of the grinder upon the shaft as its axis and to be shifted longitudinally of the shaft by means of the carrier 23, the carrier 20 wheels 36 traveling upon stationary sleeves 37 which are arranged telescopically of shaft 3. In its normal relation to the work, the grinder is suspended at a substantial angle to the vertical, as best shown 25 in Figs. 2 and 3, being supported when not in work by a bar or brace 39,—thus when the grinder is in operation its suspended weight bearing against the work will be sufficient, with but slight additional pressure 30 exerted by the operator through the controlling handle 33, to effect the grinding operation.

As here shown, the apparatus as a whole is comprised of two grinding units A—B, the unit A, as above described, being adapted to grind the face of the rims of the steel wheels, and unit B which will presently be described, being adapted to grind the edges of the rims and the hubs of the wheels.

40 As best shown in Fig. 3, grinding unit B differs from unit A only in the manner of supporting the work relative to the grinder,—the wheel, as here shown, being supported to present the edge of the rim
45 and the hub substantially at right angles to the grinder. To this end transverse supporting shafts 40—41 are disposed between shafts 11—12, the shafts being supported in suitable bearings and connected one with
50 the other by means of a chain 42 and sprockets 43, and having opposite work supporting rollers 44. Shaft 40, being the drive shaft, is connected to shaft 12 by gears 45—46,—gear 45 being adjustable on
55 shaft 12 to be moved into and out of mesh with gear 46 by means of a shifter lever 47. Thus rotation of the work,—the cast wheel 21, upon rollers 44 may be stopped as desired by the operator, when grinding
60 of the wheel will be continuous at one point, as at a rough spot in the metal, during the interval that the supporting rollers are stopped. To grind the opposite sides of the wheel the casting will be reversed upon
65 rollers 44.

The work supporting rollers 20-44 are adjustable as to the distance that one roller is spaced from another upon the respective shafts. Thus provision is made for supporting and grinding wheels of variable 70 face dimensions.

From the foregoing detailed description the construction and operation of my improved apparatus will be readily understood. The construction here shown is of a preferred form but suitable modifications may be made thereof to suit the character of the work and conditions of operation without departing from the underlying principle of the invention. 111 75 80

It will be obvious that the manual labor required to operate the grinder is reduced to the minimum by the manner of suspending the grinding units so that the grinding pressure will be generated by the weight of the grinding head, thus the operator will have little to do other than to direct the movements of the apparatus. The element of danger is practically removed by the effective manner of guarding the grinding disc and the distance that the operator is removed from the disc while at work,—the rotation of the disc being in the opposite direction from the operator. 85 90

Having described my invention what I 95
claim is:

1. In a machine of the character described, the combination with power transmission mechanism, of opposite parallel shafts, operatively connected to said power mechanism and having work-supporting means thereon, reduction gearing between the power mechanism and said shafts, overhead power transmission mechanism, a grinder suspended from and operatively connected to the overhead mechanism and means to swing the grinder at right angles and shift the same axially relative to said overhead mechanism. 100 105

2. In a machine of the character described, the combination with power transmission mechanism, of opposite parallel shafts operatively connected to said power mechanism and one with the other to rotate in unison and having work supporting means operably supported thereon, reduction gearing between the power mechanism and said shaft, overhead power transmission mechanism, a grinder suspended from and operatively connected to the overhead mechanism and means to swing the grinder at right angles and shift the same axially relative to said overhead mechanism. 110 115 120

3. In a machine of the character described, the combination with power transmission mechanism, of work supporting and work actuating means operatively connected to said power mechanism, work-speed regulating means between the work supporting means and said power mechanism, overhead power transmission mechanism, a grinder 130

suspended from and operatively connected to the overhead mechanism and means to swing the grinder at right angles and shift the same axially relative to said overhead mechanism.

4. In a machine of the character described, the combination with power transmission mechanism, of work supporting and work actuating means operatively connected to said power mechanism, means to adjust the work supporting means for work of variable dimensions, overhead power transmission mechanism, a grinder suspended from and operatively connected to the overhead mechanism and means to swing the grinder at right angles and shift the same axially relative to said overhead mechanism.

5. In a machine of the character described, the combination with power transmission mechanism, of opposite parallel shafts, operatively connected to said power mechanism and having work-supporting means thereon, reduction gearing between the power mechanism and said shaft, overhead power transmission mechanism, a grinder suspended from and operatively connected to the overhead mechanism at a

suitable angle to cause the grinder by its own weight to rest against the work, means to exert additional pressure of the grinder on the work by manual pressure as the grinding operation is being effected, and means to swing the grinder at right angles and shift the same axially relative to said overhead mechanism.

6. In a machine for grinding the rims and hubs of steel wheels, the combination with power transmission mechanism, of work supporting means operatively connected to said power mechanism and adapted to support said wheels and rotate the same suitably for the different grinding operations, overhead power transmission mechanism, a grinding apparatus suspended from and operatively connected to said overhead mechanism, whereby said grinding operations can be effected, and means to render certain of the work supporting means inoperative to effect continuous grinding on portions of said wheel.

In testimony whereof, I affix my signature.

JACOB J. WALTHER.
